METHOD AND MACHINE FOR TRIMMING TOP LIFTS

Application filed January 14, 1928. Serial No. 246,734.

This invention relates to machines for trimming the breast edges of top lifts of shoe heels, such as Cuban heels.

The top lift is usually made of leather or similar material and is secured in any suitable manner to the wooden heel with its untrimmed breast edge projecting somewhat beyond the breast of the heel. In finishing the heel it is necessary to trim the lift to conform with the shape of the breast of the heel. Heretofore, a knife or cutter acting against a cutting block was employed for this purpose. By this practice, the cutter was wedged between the lift and the partially severed chip and further movement of the cutter caused the partially severed chip to exert strain upon the body of the lift tending to tear the grain and leave an irregular edge instead of shaving the lift cleanly.

It is an object of the present invention to overcome this difficulty and provide a machine in which the partially severed chip may be moved freely out of the path of the knife and be left unsupported thereby minimizing danger of tearing the grain of the lift. With this in view a plate is provided terminating in a shearing edge cooperating with the trimming knife, the knife and plate being moved relatively to trim the lift, and the chip, or portion trimmed off, being left unsupported, thereby avoiding tearing of the grain and insuring a clean cut edge.

It is desirable that the surface of the trimmed and finished breast edge of the toplift be, as nearly as possible, a smooth continuation of the surface of the breast of the heel proper without any abrupt break, in the nature of either an offset or an angle, at the line of joint between the heel and toplift. In toplift breast trimming machines as heretofore constructed and arranged, the heels with their attached toplifts have been supported for the action of the knife by the cutting block and positioned with relation to the path of movement of the knife by said block and by suitable gauges or other positioning devices associated therewith. In adapting such machines for heels of different styles and sizes, particularly where variations in the angle formed by the breast with the outer face of

the toplift were involved, it was necessary to replace the cutting block by one of different shape, or to adjust its position, in order to support the heel with its breast surface as nearly as possible coincident with the surface generated by the relative movement of the knife edge and work. This mode of control is slow and inconvenient, requiring frequent readjustments, is indirect, and is at best approximate, depending upon the capacity of the parts for accurate adjustment and the human element involved in making the adjustments. In accordance with the present invention the desired result is accomplished positively and directly, without adjustment and irrespective of the size and shape of the heel, by holding the breast of the heel against the face of the knife during the cutting operation, and permitting the face of the toplift to assume whatever position may be required by its angular relation to the heel breast, so that as the knife edge passes from the heel breast surface through the toplift it will cut the latter along a surface which is a smooth continuation of the former. This is made possible by providing a supporting plate which terminates in an edge lying substantially in the surface generated by the relative movement of the knife edge and work, leaving the projecting portion of the toplift unsupported, so that the face of said toplift can be supported solely by said edge and turned thereabout into whatever angular position may be necessary in order to position the breast of the heel against the face of the knife, and held in this position during the cutting operation. In machines employing a cutting block, the face of the toplift must lie flat on the block during the cutting operation.

Before explaining the invention in detail it is pointed out that the embodiment herein described is merely by way of illustration and that it is not intended to limit the invention thereby except as pointed out by the appended claims.

The invention will be more clearly understood from the following description in conjunction with the accompanying drawings, in which,

Fig. 1 is a plan view of a machine embodying the invention;

Fig. 2 is an end elevational view of the same;

Fig. 3 is a sectional view taken upon the line 3—3, Fig. 2.

Fig. 4 is a detail elevational view showing the method of guiding the heel during the trimming operation by positioning the breast thereof against the breasting knife; and

Fig. 5 is a similar detail view showing the action of the cooperating breasting knife and shearing edge.

As illustrated, the machine comprises a base or frame 10 adapted to rest upon a suitable support, such as a table 11, to which it is secured in any suitable manner, as by bolts 12. The frame 10 is provided with a projection 14 to which a trimming knife 15 is secured by clamps 16 engaging the knife and frame and secured to the latter by bolts 17. The surface of the knife is shaped to conform to the surface of the breast of the heel. The upper edges of the knife 15 and projection 14 of the frame are covered by a plate 20 secured to the frame by bolts 21.

In accordance with the invention the heel lift may be positioned with the edge to be trimmed off unsupported between the edge of the knife 15 and a shearing edge cooperating with said knife, and, preferably, with the breast of the heel engaging the similarly shaped body of the knife. For this purpose, as illustrated, a slide 25 is provided adapted to reciprocate in the slideway 26 in the frame of the machine. As shown, the slide 25 is of cylindrical form and is prevented from turning in the way 26 by a guide pin 27 secured in the upper lateral projection 28 of the slide and guided in an opening 29 in the frame of the machine. A plate 35 is secured to the lateral projection 28 of the slide 25 by a bolt 37 passing through a counterbored opening 38 in the plate 35 and threaded in the slide. A plate 32 having a shearing edge 33 is mounted upon the plate 35 and, preferably, is in the form of a detachable and adjustable slide guided in ways 34 in the plate 35. The plate or slide 32 is provided with an opening 40 surrounding the head of the bolt 37 so that the slide may be adjusted readily and clamped with its shearing edge 33 positioned to cooperate with the knife 15 by a clamp 42 engaging the slide 32 and plate 35 and secured to the latter by a bolt 43.

The lower end of the slide 25 is provided with a threaded hole 45 to receive a bolt with a bifurcated head in which a connecting rod member 46 is pivotally secured by a pin 47. The member 46 is connected to the connecting rod member 48 by a turn buckle 49, whereby the length of the connecting rod as a whole comprising the connecting rod members 46 and 48 and turn buckle 49 may be adjusted. The end of the connecting rod member 48 is

provided with a bearing or journal 50 surrounding an eccentric 51 upon a shaft 52 which is rotatably mounted in suitable bearings 53 formed in webs 54 depending from the frame 10, the connecting rod member 48 being held upon the eccentric 51 by a screw 55 in the eccentric having a head engaging the edge of the bearing 50.

In the operation of the machine, the heel blank W, to which a lift 56 has been secured in the usual manner, is positioned in the machine with the breast of the heel engaging the surface of the knife 15 and the lift 56 resting against and supported by the shearing edge of the plate 32 during the trimming operation. As the shaft 52 is rotated, the eccentric 51 thereon causes the slide 25, through the parts connected therewith, to reciprocate relative to the knife 15 while the heel breast is held in engagement with the latter, thereby causing the knife to pass through the portion of the lift projecting beyond the breast of the heel to trim the same on a surface which is a smooth and accurate continuation of the surface of the breast.

In accordance with the invention the body of the lift may rest against the plate 32 but this is not necessary inasmuch as the heel W may be positioned and guided by placing the breast of the heel against the body of the knife 15 (as illustrated in Fig. 4) and while thus positioned permitting the plate 32 to move upward and bring the shearing edge 33 of the plate 32 into engagement with the lift. Thus, when using the machine of the invention to trim the top lifts of heels of different types and sizes it is unnecessary to replace the plate 32 by one which will engage the body of the lift during the trimming operation. As the knife passes through the lift, the portion to be trimmed off will tend to turn about the shearing edge 33 (as illustrated in Fig. 5) and fall off, and inasmuch as this portion is unsupported there will be no tendency for it to wedge against the knife and tear the edge of the lift as has been common heretofore in machines of this type.

The connecting rod may be adjusted by means of the turn buckle 49 to vary the limits of movement of the plate 32 and thereby control the position of the movable member to compensate for knife wear or for different thicknesses of toplift. By constructing the plate 32 as a detachable and adjustable slide it may be removed and replaced by slides appropriate for the type of heel and lift being trimmed and the shearing edge may be accurately adjusted to cooperate with the knife 15, although no adjustment is necessary to compensate for variations in angle between the heel breast and toplift face. It will be understood that while in the embodiment of the invention illustrated the knife is held stationary and the plate 32 supports the work and is reciprocated, nevertheless, these ar-

rangements may be reversed within the spirit of the invention.

What I claim is:

1. A machine for trimming off the projecting breast edges of toplifts attached to shoe heels, said machine comprising, in combination, a plate terminating in a shearing edge against which the toplift may rest during the trimming operation with the portion to be trimmed off projecting beyond said edge, cutting means cooperating with said shearing edge and engaging the previously formed breast of said heel to locate the toplift and determine the path of relative movement of the cutting means and work, and means for relatively moving said cutting means and plate.

2. In a top lift trimming machine, in combination, a frame, a shaft rotatably mounted in said frame having an eccentric, a slide, a plate on said slide terminating in a shearing edge against which the lift may rest, an adjustable connecting rod between said slide and eccentric for controlling the limits of travel of said plate, and a knife on said frame positioned to cooperate with said shearing edge to trim the lift as said shaft is rotated.

3. In a top lift trimming machine, in combination, a frame, a shaft rotatably mounted on said frame having an eccentric, a slide, an adjustable plate on said slide terminating in a shearing edge against which the lift may rest, an adjustable connecting rod between said slide and eccentric to control the limits of travel of said plate, and a knife on said frame positioned to cooperate with said shearing edge to trim the lift as said shaft is rotated.

4. The method of trimming the breast edge of a toplift attached to a shoe heel which includes angularly positioning the breast of a heel against the similarly shaped body of a knife with the projecting edge of the lift between the edge of the knife and a cooperating shearing edge, and relatively moving said knife and shearing edge while holding said heel breast against said knife to determine the path of relative movement of the knife and work.

5. The herein described method of trimming the breast edge of a toplift attached to a shoe heel which includes positioning the breast of a heel against the similarly shaped body of a knife, supporting the outer face of the toplift along the line of cut leaving the portion to be trimmed off unsupported, and relatively moving the knife and support to cut the toplift through from its face adjacent the heel while holding said heel breast against said knife to determine the path of relative movement of the knife and work.

6. The herein described method of trimming attached toplifts which includes supporting the exposed face of the toplift at that side only of the line of cut opposite the por-

tion to be trimmed off, leaving said portion unsupported, and cutting said toplift through from the opposite face.

7. The herein described method of trimming attached toplifts which includes supporting the exposed face of the toplift at that side only of the line of cut opposite the portion to be trimmed off and substantially throughout the length of said line, leaving said portion unsupported, and cutting said toplift through from the opposite face by a single cutting operation directed toward the support.

In testimony whereof I affix my signature.
